UNITED STATES PATENT OFFICE.

NATHAN WEISS, OF NEW YORK, N. Y., ASSIGNOR TO AMERICAN CIGAR COMPANY, OF NEW YORK, N. Y., A CORPORATION OF NEW JERSEY.

DESIGN FOR A BOX OF CIGARS.

44,673.

Specification for Design.

Patented Sept. 16, 1913.

Application filed September 11, 1908. Serial No. 452,672. Term of patent 3½ years.

To all whom it may concern:

Be it known that I, NATHAN WEISS, a citizen of the United States, residing at New York, in the county of New York and State of New York, have invented a new, original, and ornamental Design for a Box of Cigars, of which the following is a specification, reference being had to the accompanying drawing, forming part thereof, and wherein the box of cigars is shown in perspective with the lid of the box open as the same is arranged for exhibition in a showcase or other place of sale.

The leading characteristics of the design are shown in the drawing, wherein the reference numeral 2 designates the box body having front wall 3, side walls 4, 5, and rear wall 6, from the ends of which rear wall project forwardly within and lying against the side walls 4, 5, arms 7 which extend forward somewhat more than one-half the distance to the front wall 3, and which terminate and merge into the side walls 4, 5 in tapering ends 8, the appearance of the rear wall and the arms projecting forwardly from the ends thereof being that of a yoke set in between the side walls of the box. Within

the box are disposed cigars 9 in two rows, the butt or lighting ends of the cigars 10 resting against the front and rear walls, and the head or mouth ends of the cigars tapering as shown at 11, the heads of the two rows of cigars overlapping and nesting together as illustrated: the end cigars of the front row contacting with the forward portions of the side walls 4, 5, and the end cigars of the rear row contacting with the forwardly extending arms 7. The side walls project above the front wall and also above the arms 7, and the rear wall. The lid of the box, 12, when closed lies between the side walls and in contact with the upper edges of the front and rear walls and the forwardly projecting arms 7.

The design as an entirety presents a box of cigars of artistic attractiveness.

I claim:—

The ornamental design for a box of cigars as shown and described.

NATHAN WEISS.
